SPLINT

Franklin I. Saemann and Franklin I. Saemann,
Jr., Oak Park, and Robert Gennat, Chicago, Ill.,
assignors to Ambulatory Pneumatic Splint
Mfg. Co., Chicago, Ill., a corporation of Illinois

Application January 6, 1933, Serial No. 650,376

10 Claims. (Cl. 128—85)

The present invention relates to splints of the type illustrated in United States Letters Patent No. 1,196,837, dated September 5, 1916, and has for its object to improve the same and the functions thereof.

5 Ordinarily the bones of fractured legs cannot be set until the swelling induced by the fracture has subsided. One of the objects of the present invention is so to improve the splint of the aforesaid patent or other extensible leg splints, as to make it possible to set broken bones without waiting for the swelling to subside and without causing undue discomfort to the patient.

10 A further object of the present invention is to equalize the traction between the ankle and a part 15 of the leg higher up when the pull or traction on the leg is divided between these two points.

15 A further object of the present invention is to insure that the pull on the leg, in securing traction and counter-traction, is yieldable.

20 A further object of the present invention is to produce a simple and novel splint that provides constant traction not only when the patient is resting but when he is walking about on the splint.

25 Viewed in another of its aspects, the present invention may be said to have for its object to produce a simple and novel splint to be applied in the case of a fracture of a leg or thigh, the same being provided with means for exerting constant 30 yielding traction and counter-traction and automatically taking up any slack which would otherwise occur.

35 Viewed in another aspect, the present invention may be said to have for its object to produce a simple and novel splint of the character specified, in which there is provided an indicating device which shows at all times the degree of traction and counter traction.

40 A further object of the present invention is to make it possible quickly and easily to lengthen and shorten a splint by electric motor means, whereby a desired amount of traction may be quickly obtained through a uniform pull and whereby, further, it becomes a simple matter to produce spasmotic traction.

45 The various features of novelty whereby our invention is characterized will hereinafter be pointed out with particularity in the claims; but, for a full understanding of the invention and of its objects and advantages, including the foregoing objects and others, reference may be had to the following detailed description taken in connection with the accompanying drawings, wherein:

Figure 1 is a side elevation of one of our improved splints, showing a motor connected to the same for extending it; Fig. 2 is a bottom plan view, on a larger scale, of the compound key which is the same as that illustrated in said Patent 1,196,837; Fig. 3 is a view on a larger scale than Fig. 1 showing the manner of detachably fastening the bracket of a hip joint attachment to the main posts or columns of the splint; Fig. 4 is a view, partly in section, on line 4—4 of Fig. 3, and partly in elevation; Fig. 5 is an elevation of the lower end of one of the columns or posts, showing the graduations which indicate the amount of pull or traction at any given time; Fig. 6 is a section, on the same scale as Figs. 3 and 4, 10 on line 6—6 of Fig. 1; and Figs. 7 and 8 are longitudinal sections, in planes at right angles to each other, through the lower end of the splint.

The main portion of the splint shown in the drawings comprises four long extensible rods or 20 posts on the upper end of which is a seat cushion 1 and on the lower end of which is a foot plate 2. Each rod or post is made of two telescoped tubes 3 and 4. Within each of the tubes 4 is a long rod 5 rotatable in the tube but held against lengthwise 25 movement relatively thereto. The upper end of each rod is screw-threaded, as indicated at 6, the screw threads on the rod meshing with internal screw threads 7 in the corresponding upper tubular section 3. These parts, together with the compound key 8, which is detachably connected to the lower end of the splint and provided with elements 9, 9, to be engaged by a tool or other driving element to turn the rods and thus lengthen or shorten the posts, may be the same as the corresponding elements illustrated in said Patent 1,196,837, and require no further discussion. Within the lower end of the splint is any usual or suitable ankle cushion 10 adapted to be secured around the ankle of the wearer. The ankle cushion is preferably in the form of a canvas shoe lined with lamb's wool and containing air pockets so as to provide not only the cushioning effect of the wool but also of pneumatic cushions. Heretofore the ankle cushion has been connected to the 40 foot plate by straps and, where divided traction has been sought, the foot plate has also been connected, by means of straps and adhesive tape, to a point on the leg just below the fracture. With such an arrangement, there is no give to the pull or traction and the doctor or operator applying the splint has no means of knowing how powerful the pull is at any given time.

45 In accordance with the present invention, the connections with the ankle and the leg are not 50 55

positively attached to the foot plate, but there is interposed spring means which are stressed as traction is applied. Consequently, the pull is always a yieldable one although it may be quite 5 powerful. The spring means is preferably of such a character as to act to equalize the pull between the ankle and the leg just below the fracture.

When the splint is extended to produce traction, the force of the pull will be represented by 10 the degree of stressing of the spring means. Therefore, the spring means may be made to serve as an indicator to show the force of the pull or traction at any given time.

We have discovered that, while it is usually 15 possible to set a broken bone before the swelling has subsided, by simply immobilizing the leg in the splint and extending the splint the required amount, because of the great pain caused the patient: Yet, if a little traction is applied and then 20 released, and then a little greater traction which, also, is released, and so on, the bone may be set quickly and easily, without causing the patient to suffer severe pain, and without waiting for the swelling to subside. By providing an indicator to 25 show the degree of stressing of the spring means at all times, it becomes a simple matter alternately to apply and release a pull or traction which is gradually built up.

Ordinarily traction is secured by means of a 30 little hand tool applied to one of the tool-receiving parts 9 of the compound key, but this is a slow way of contracting and extending the splint. Therefore, in order to render effective the method 35 of setting a bone by alternate application and release of the pull which is gradually built up, it is necessary to provide power means to extend and contract the posts of the splint. To this end, as best shown in Fig. 1, we have provided a small portable power plant consisting of an electric 40 motor A, a reversing switch B, and a rheostat C. The motor drives a flexible shaft D on the free end of which is a head E, like the head of a wrench, which may be detachably fitted over one 45 of the elements 9 on the compound key. Current for operating the motor may be obtained through 50 a suitable cord F adapted to be plugged into any suitable light or wall socket. After the splint has been applied and the power plant connected, the motor is started and is allowed to run until the 55 desired preliminary pull or traction is obtained, whereupon the motor will be reversed so as to release the pull or traction. The speed of extension of the splint may at all times be controlled by means of the rheostat, so that the pull, whether it be ultimately great or small, may be built up gradually or rapidly, as may be desired.

The springs for permitting yielding traction to be obtained and for equalizing the pull or traction may conveniently be housed in the lower 60 sections 4 of the tubular posts. Since the screw rods must enter the upper smaller tubes 3 of the posts, they are, of course, smaller in diameter than the internal diameter of the tubes 4; thus providing around each rod, within each tube 65 4, an annular space to receive and house a long compression spring 11. There are four of these springs, one at each post. Each spring rests at its lower end on a short sleeve or bushing 12 which in turn rests on an internal annular shoulder 70 13 in the post. Engaged with the upper end of each spring is a follower 14 in the form of a short sleeve overlying the spring. Each tube 4 has a slot 15 extending lengthwise thereof from the lower end to a considerable height. The followers 14 in the two tubes on the same side of

the splint are connected together by a rod or shaft 16 which extends through the slots 15. These rods or shafts serve as stops to limit the upward movement of the followers, since the followers can move upwardly only until the rods or shafts come to a stop in the upper ends of the slots in the posts. The posts are so proportioned that the springs are under an initial compression when they have expanded as far as the followers will permit. When the bars or shafts 16 are pushed down toward the foot plate, further compression of the springs occurs, the force required to effect further compression increasing as the degree of compression of the springs increases. On each of the rods or shafts 16 are 15 two loose, semi-cylindrical trough-like parts 17 fitting against the posts and held against lateral movement away from the posts by shoulders 18 on the rods or shafts. One of these trough-like members 17 may be utilized as the pointer of a graduated indicator adapted to show the degree of pull or traction at any given time. Thus, as shown in Fig. 5, one of the posts 4 may be provided with a series of graduations 19 distributed lengthwise thereof just below the corresponding member 17 when the latter is in its raised position. These graduations may be numbered to indicate the force of the pull in pounds. In the arrangement shown, the graduations are numbered 20, 40, 60, 80, 100 and 120. Whenever the 30 pointer member 17 is moved down to one of the graduations, it will be known that the force of the pull in pounds is equal to the number associated with that graduation.

On each of the rods or shafts 16 is a roller 20. 35 Attached to the ankle cushion are two straps 21, 21, each attached at one end to the cushion. On the foot plate are pairs of rollers 22, 22, parallel with the rollers 20. The rollers 22 may conveniently surround the studs 23 which, as in 40 Patent 1,196,887, hold the foot plate against separation from the lower ends of the posts.

In using the splint, each strap is carried down underneath one of the corresponding rollers 22, up over the roller 20 on the same side of the 45 splint, diagonally back down under the other roller 22 of the pair and then up on the inside of the splint; the free end of the strap being connected to the lower end of a broad piece of adhesive tape 25, which is attached to the leg 50 just below the fracture. Each strap may have therein a buckle 24. The straps may be secured to the ankle cushion in any suitable manner. When the splint is extended, traction on the leg results from the downward pull of the rollers 22 55 on the loops in the straps 21 engaged therewith. As the leg offers resistance to stretching, the springs are compressed until a point is reached at which the resistance of the leg is overcome and it begins to stretch. Thus there is always 60 the offsetting of the resistance offered by the leg against the force of the spring, the pull on the leg being therefore always a yieldable one and being built up gradually instead of being suddenly imposed thereon. Furthermore, the divided pull on the leg is equalized between the 65 ankle and the point higher on the leg so that traction is not only yieldable and steady but is also even.

It should be noted that not only does our improved spring equalizing device make it a simple matter to secure spasmotic traction, or simply any desired degree of traction and counter-traction, while informing the surgeon at all times just how strong a pull is being exerted; but, when a pa- 70 75

tient is walking about, and his hip and leg move up and down in the splint due to the yieldable nature of the hip cushions or pads and of the muscular and fatty tissue of the patient resting on that cushion or pad, the spring equalizing device keeps on pulling and compensates for the up or down movement of the leg and hip. As a result effective traction and counter-traction are maintained during walking and the patient need not fear that the pull will be released and the meeting ends of the bones slip past each other or, as an alternative, that constant watch must be kept in order to ensure against the latter happening. Not only is there safety in walking, but there is just enough irritation of the knitting joint to cause a better joint to result than would be the case if it had not been exercised.

It frequently is necessary to employ a hip joint attachment, as explained in said Patent 1,196,887. 20 One of the features of the present invention has to do with the means for securing such an attachment to the splint. In the arrangement shown, as will best be seen in Figs. 3 and 4, there are two double-ended sockets 27, 27 secured to the metal foundation 28 of the seat pad or cushion, the axes of the sockets being vertical. The upper ends of the members 3 of two of the posts, containing plugs as indicated at 29, are entered into the lower ends of these sockets. Consequently, the 30 seat cushion or pad may be detached by simply separating the posts from the sockets. The hip joint attachment 30 has two stem-like supports 31 the lower ends of which may be slipped into the upper ends of the sockets when the attachment 35 is to be applied to the splint. A very simple way of securing the ends of the posts 3 and the members 31 in the sockets is to provide each socket with two keyhole slots 32 opening out of the ends thereof. Then by screwing a headed screw 33 40 radially into each post and each stem 31 at the proper distance from the end, slip joints are provided while the screws project far enough for their heads to clear the outer surfaces of the sockets; and, when the parts are assembled, and 45 the screws are screwed in until the heads thereof rest in the large ends of the keyhole slots, the posts and the stems are securely locked together.

In Fig. 1 we have illustrated the usual thigh and leg cushions 35 and 36, respectively; these 50 cushions being secured to suitable slides each extending between and adjustably secured to two of the tubes 3. As best shown in Fig. 6, each slide is composed of two long, narrow stiff plates 37 and 38 each having concave seats 39, 39 on the inner side near opposite ends. A bolt 49 passes through the middle of the plates. When a pair of the plates is placed on opposite sides of two of the tubes 3, with the tubes engaged in the concave seats, and the nut 41 on the bolt is tightened, 60 the tubes are clamped tightly between the plates which are then immovable on the tubes. The thigh and leg cushions 35 and 36 have therein slits 42 through which the nuts 41 may be inserted. The nuts 41 are made fairly long so as to 65 constitute short bars which span the slits and clamp the cushions to the slides; the tightening of one of the nuts securing a cushion to the corresponding slide and simultaneously clamping the slide to the tubular members of the splint.

70 While we have illustrated and described with particularity only a single preferred form of our invention, we do not desire to be limited to the exact structural details thus illustrated and described; but intend to cover all forms and ar-

rangements which come within the definitions of the invention constituting the appended claims.

We claim:

1. The combination with a leg splint of the lengthwise extensible type having at its upper end a seat pad and at its lower end an ankle cushion adapted to surround the ankle of the wearer, of a flexible element connected at one end to said ankle cushion and adapted to be connected at its other end to the leg below the fracture, and means including a spring device slidably connecting the said flexible element to the lower end of the splint; whereby yieldable traction and counter-traction are secured when the splint is extended. 5

2. The combination with a leg splint of the lengthwise extensible type having at its upper end a seat pad and at its lower end an ankle cushion adapted to surround the ankle of the wearer, members on the lower end of the splint 10 at some distance apart in the direction of the length of the splint and one of them movable lengthwise of the splint, a compression spring between said members, a strap looped about said members and in sliding engagement therewith 15 so that a pull on the ends of the strap will cause said spring to be compressed, one end of the strap being attached to said ankle cushion and the other end being adapted to be attached to the leg of the wearer of the splint below the 20 fracture. 25

3. The combination with a leg splint of the lengthwise extensible type adapted to secure traction and counter-traction on the leg of a wearer and having four tubular posts formed in 30 sections in telescoped relation to each other, means to extend and shorten said parts, of springs in the lower portions of the posts, followers resting on the springs, the two followers 35 on each of two opposite sides of the splint being connected together by a rod, the posts being slotted to permit said rods to be moved up and down, two stationary rods on the lower ends of the splint parallel to the aforesaid rods, and two straps each adapted to be looped around the movable rod and the corresponding stationary rod on one side of the splint and be secured at its 40 ends to two points on the leg of the wearer separated from each other lengthwise of the leg. 45

4. In a splint, a seat pad, a foot plate, posts 50 rising from the foot plate into the vicinity of the seat pad, double-ended sockets mounted on the seat pad with the axes of their openings arranged vertically, the upper ends of certain of the posts fitting into the lower ends of said 55 sockets, a hip joint attachment having supporting stems each adapted to be fitted into the upper end of one of said sockets.

5. The combination with a leg splint of the lengthwise extensible type to secure traction and counter-traction on the leg of the wearer, of a flexible device looped under a part on the lower end of the splint and in sliding engagement therewith, an ankle embracing cushion connected to one end of said flexible device, and the 60 other end of said flexible device being adapted to be attached to the leg of the wearer of the splint below the fracture, whereby the pull on the leg, upon extension of the splint, will be 65 equalized between the ankle cushion and the higher point of attachment of said flexible device with the leg. 70

6. The combination with a leg splint of the lengthwise extensible type having at its upper 75

end a seat pad and at its lower end an ankle cushion adapted to surround the ankle of the wearer, of a flexible device connected at one end to the ankle cushion and adapted to be attached 5 to the leg of the wearer at a point above the ankle and below the fracture, and a part on the lower end of the splint below the ankle cushion slidably engaged with said flexible device to equalize the pull at the two ends of said device 10 when the splint is extended.

7. The combination with a leg splint of the lengthwise extensible type having at its upper end a seat pad and at its lower end an ankle cushion adapted to surround the ankle of the 15 wearer, of a flexible device connected at one end to the ankle cushion and adapted to be attached to the leg of the wearer at a point above the angle and below the fracture, and means including a spring yieldingly connecting said flexible device to the lower end of the splint, said means having a sliding connection with said flexible device below the point of attachment of the latter with the ankle cushion, whereby the pull on the leg of the wearer of the splint when the 20 splint is extended is yieldable and is equalized between the opposite ends of said flexible device.

8. The combination with a leg splint of the lengthwise extensible type having at its upper 25 end a seat pad, and an ankle cushion adapted 30 to be inserted in the lower end of the splint, of a long flexible element connected at one end to said cushion and adapted to be connected at its other end to the leg below a fracture therein, and means including a part of the splint below 35 said cushion over which said flexible element passes to produce a sliding connection between said flexible device and said splint and thereby

cause an equalized traction and counter-traction to be obtained when the splint is extended.

9. The combination with a leg splint of the lengthwise extensible type having at its upper 5 end a seat pad and at its lower end a cross bar, together with an ankle cushion adapted to be placed within the splint above said cross bar, of a flexible element connected at one end to said ankle cushion and adapted to be passed down underneath said cross bar and be connected at its other end to the leg below the fracture, whereby the pull on the ankle cushion and on the leg at said point below the fracture will be equalized when the splint is extended.

10. The combination with a leg splint of the lengthwise extensible type having at its upper 10 end a seat pad, together with an ankle cushion adapted to be inserted in the lower end of the splint, of a fixed cross bar at the lower end of the splint below the position adapted to be occupied by the ankle cushion, of a second cross bar mounted on the splint above the ankle cushion position and slidably mounted so as to be movable from and toward the other cross bar, a compression spring carried by the splint and tending constantly to move the second cross bar upward and away from the first cross bar; and a flexible element connected at one end to said ankle cushion, and adapted to be carried underneath the first cross bar, up over the top of the 15 second cross bar, down under the first cross bar, and then up and attached to the leg below the fracture, whereby yieldable, equalized traction and counter-traction are secured when the 20 splint is extended.

FRANKLIN I. SAEMANN.

FRANKLIN I. SAEMANN, JR.

ROBERT GENNAT.
